UNITED STATES PATENT OFFICE.

WALTER SCOTT, OF PLAINFIELD, NEW JERSEY.

DELIVERY APPARATUS FOR PRINTING-MACHINES.

SPECIFICATION forming part of Letters Patent No. 317,218, dated May 5, 1885.

Application filed December 28, 1883. (No model.)

To all whom it may concern:

Be it known that I, WALTER SCOTT, of Plainfield, in the county of Union and State of New Jersey, have invented an Improvement in Delivery Apparatus for Printing-Machines, of which the following is a specification.

This invention relates to a fly-frame for moving the grippers that receive the sheet as delivered from the impression or transfer cylinder and deliver the same upon a table.

In the drawings, Figure 1 is an elevation, partially in section, representing the fly-frame and grippers and their actuating devices. Fig. 2 is a detached elevation of the fly-frame at one side. Fig. 3 shows the grippers in the position they assume when delivering the sheet upon the table. Fig. 4 shows the gripper when about to take the sheet from the impression or transfer cylinder. Fig. 5 is an elevation at one side of the upper part of the fly-frame and of the parts carried by it.

The impression-cylinder B is adapted to receive the sheet from the feed-board d or other source of supply. The printing-surface may be a cylinder or the form A upon a reciprocating bed, and a transfer-cylinder, C, may be used between the impression-cylinder and the delivery-fly, or else the sheet may be taken directly from the impression-cylinder. Where the impression-cylinder makes two revolutions to each impression, or where it makes one revolution as the types move beneath it and remains stationary during the return movement of the bed, the sheet may be taken off the front of the impression-cylinder and laid with the printed side uppermost upon the delivery-table d', (shown by dotted lines in Fig. 1,) the fly-frame and delivery-grippers and actuating devices, hereinafter described, being available for use with the delivery-table in this position, or when they are beneath the feed-table, as shown by full lines, for taking the sheet from the impression or transfer cylinder.

In order to take the sheet when printed, I make use of the fly-frame R, composed of two arms upon the rock-shaft r, such arms being far enough apart to allow the sheet to swing between them as held by the grippers s s'. The grippers s are hung from the rock-shaft t, and each gripper is in the form of a bent

arm, and through the arms s' on the shaft t passes the shaft t', that carries the gripper-fingers s', and at the end of the shaft t' is a crank or wrist, 3, and upon the fly-frame R is a stationary cam, 4. When the shaft t 55 and grippers are swung into the position shown in Fig. 4, the cam 4 opens the grippers to receive the sheet. The moment the shaft t is turned in the direction in which the sheet is moving when passing into the grippers 60 the cam 4 allows the grippers to be closed by a spring, 5, and hold the sheet, and when the fly-frame has been swung down into proximity to the delivery-table d' the grippers are opened by the shaft t receiving sufficient of a turning 65 motion to bring the crank-arm at the end of the shaft t into contact with the other part of the cam 4 and open the grippers and discharge the sheet. I give to the fly-frame R a swinging motion by a crank-pin, 6, on the wheel b 70 or eccentric, and rod e, connected with the fly-frame or with a crank-arm, e', upon the rock-shaft r, so that the fly-frame will be brought up into position for the grippers to receive the sheet at the proper time, and such sheet 75 will be carried by the fly-frame and grippers and laid down upon the table.

To prevent the sheet sliding down the inclined table and blurring the impression, I provide a foot-board, h, that is connected to the 80 table by slotted angle-irons and clamping-screws h', so as to be placed in the proper position, according to the length of the sheet, for the end of the sheet to be supported by the foot-board as the sheet is dropped from the grippers.

In order to turn the rock-shaft t of the grippers at the proper time for opening the grippers and allowing them to close, I provide a pinion, 10, on the rock-shaft t, a rack, 11, 90 gearing into the same, a rod, 12, in slides on the fly-frame, a rack, 18, at the other end, and a pinion or wheel, 14, loose upon the rock-shaft r, and to this wheel 14 motion is given at the proper time by a cam, v, upon the shaft 95 A', acting upon a slide-rod, 19, and rack 13, supported by a roller or by a guide. I have shown a supporting-guide, 17. The rack 13 is preferably placed so as to act directly upon the gear 14, and the cam v is shaped so that it 100

moves the racks and pinions to turn the shaft t and grippers and allow the grippers to close as the edge of the sheet passes into them, then to swing the grippers with the sheet as the 5 fly-frame moves, and to continue the swinging movement of the grippers with the rock-shaft until the stationary cam opens the grippers and delivers the sheet upon the table.

If desired, the sheets are guided accurately 10 to place one above the other upon the delivery-table by the side and end boards, h^2 h , each of which is perpendicular to the table at the portion which is adjacent to such table, and at an inclination thereto in the upper part, so that 15 the sheet sliding down the incline as delivered is brought to place between the vertical faces of the side and end boards. In Fig. 1 only a portion of the delivery-table is shown.

The fly-frame and rock-shaft, when placed 20 for delivering the sheets from the front side of the impression-cylinder, may be located as shown by dotted lines in Fig. 1, or in any other desired position, so as to deliver the sheets upon an inclined table or upon a level 25 table, as indicated by the dotted lines.

In order to cause the sheet to be properly 30 laid upon the delivery-table after it is taken from the impression-cylinder, I make use of the delivery-cylinder C and the fly-frame R, with grippers at the outer end to receive the 35 advancing end of the sheet and convey the same outwardly and downwardly to the table, and an air-pipe with jets, beneath which the sheet is drawn by the fly and grippers so as to force the back end of the sheet down upon the table.

The gear-wheels b^3 b^4 b^5 serve to connect the impression-cylinder B with the shaft A', so that the two will revolve in unison, and it is 40 necessary that the shaft A' shall revolve once for each two revolutions of the impression-cylinder, so that the fly-frame may take off each sheet as printed.

I do not limit myself to the precise construction 45 of the grippers and their rock-shaft, as these may be varied.

In my improved press the impression-cylinder or the delivery-cylinder becomes a revolving sheet-carrier with grippers or other 50 sheet-retaining mechanism, and I remark that

the counterpoise e^3 may be variable, so as to lessen concussion and cause the swinging fly-frame to move with uniformity.

I do not herein claim a fly-frame with a cross-shaft carrying gripper-fingers, and a second shaft with grippers, as the same is set forth in my application filed December 28, 1883, Serial No. 115,823.

I claim as my invention—

1. The fly-frame and its rock-shaft, in combination with grippers, a rock-shaft at the outer end of the fly-frame carrying such grippers, a stationary cam for opening or closing the grippers, and a positive-motion mechanism, substantially as specified, for swinging 65 the fly-frame and grippers, and mechanism, substantially as specified, for opening the grippers by contact with the stationary cam, and a spring to close such grippers, substantially as set forth.

2. The combination, with the fly-frame and grippers for delivering the sheet, of a pinion at the axis of the fly-frame, a rack and cam to move the same, and a rack upon the fly-frame, receiving motion from the pinion and 75 acting to move the grippers for opening and closing the same, substantially as set forth.

3. The combination, with the fly-frame and grippers, of a crank and connecting rod for giving motion to the fly-frame, the rack 13, 80 pinion 14, and a rack on the fly-frame and pinion 10 on the gripper rock-shaft, and cams for giving motion to the parts, substantially as set forth.

4. The combination, with the delivery-cylinder C, of a fly-frame, R, and grippers at the outer end thereof to receive the advancing end of the sheet and convey the same outwardly and downwardly to the distant end of the delivery-table, and an air-pipe with jets, beneath 90 which the sheet is drawn by the fly and grippers, whereby said air-jets force the back end of the sheet down upon the table, substantially as specified.

Signed by me this 20th day of December, 95
A. D. 1883.

WALTER SCOTT.
